UNITED STATES PATENT OFFICE

HERBERT MOLLER, OF DUNKIRK, INDIANA, ASSIGNOR TO INDIANA GLASS COMPANY,
OF DUNKIRK, INDIANA, A CORPORATION OF INDIANA

DESIGN FOR A PLATE OR SIMILAR ARTICLE

Application filed February 6, 1933. Serial No. 47,126. Term of patent 14 years.

To all whom it may concern:

Be it known that I, HERBERT MOLLER, a citizen of the United States, and resident of Dunkirk, county of Jay, State of Indiana, have invented a new, original, and ornamental Design for a Plate or Similar Article, of which the following is a specification, reference being had to the accompanying drawing, forming a part thereof.

In the drawing:

Figure 1 is a plan view of a plate, the design unit being shown in detail. This unit is continued about the other three quarters of the plate in regular succession.

Figure 2 is a cross section on the line 2—2 of Figure 1.

The design consists of a floral decoration applied in relief, as shown in the drawing, to a substantially annular portion of a plate or similar article. It is contemplated to apply the design of this case to plates generally, platters, covers or analogous articles.

I claim:

The ornamental design for a plate or similar article, substantially as shown and described.

In testimony whereof I have hereunto signed my name to this specification.

HERBERT MOLLER.
